UNITED STATES PATENT OFFICE.

JOHN A. RAY, OF KISSIMMEE, FLORIDA.

VENDING MACHINE.

Application filed May 15, 1924. Serial No. 713,552.

To all whom it may concern:

Be it known that I, JOHN A. RAY, a citizen of the United States, residing at Kissimmee, in the county of Osceola and State of Florida, have invented or discovered certain new and useful Improvements in Vending Machines, of which the following is a specification, reference being had thereto in the accompanying drawings.

10 This invention relates to a coin-controlled vending machine which is adapted for use in connection with various kinds of articles placed on sale, and the invention has for its object to provide a machine of this kind 15 which is simple in construction and easily operated, the article carrier of said machine being somewhat varied in construction, according to the articles with which the machine is intended to be charged or 20 loaded, so that the machine may be used in connection with all kinds of small articles, as cigars or cigarettes, or with various kinds of larger articles, as packages of tobacco or cakes of soap, as may be desired.

25 In the accompanying drawings Fig. 1 is a front view of the improved machine, Fig. 2 a side view of the same with the side casing omitted, Fig. 3 a vertical section of the same, Fig. 4 is a detail view of a portion 30 of the operating mechanism.

Referring to the drawings, 12 denotes a suitable casing within which is a suitable framework 13. Journalled in an upright portion of the framework 13 are two drums 35 14 and 15. Attached at its opposite ends to the said drums 14 and 15 is a flexible carrier consisting preferably of sprocket chains 16 to which are attached cross bars or plates 17 having outwardly projecting 40 parts or flanges 18 between which the articles to be sold are placed, and these flanged cross plates, which serve as holders for the articles, will be of any size according to the kind of goods with which the vending 45 machine is to be charged. The flexible carrier in running from the drum 14 to the drum 15 passes around a roller 19 which is provided with pins 20, these pins forming sprocket wheel portions adapted for engagement with the sprocket chains 16.

A proper tension for holding the flexible carrier taut is secured by means of a volute spring 21 connected directly with the shaft 15^a to which the drum 15 is attached.

50 Mounted on said shaft is a ratchet wheel

22 engaged by a spring-pressed detent pawl 23, so that the said spring 21 may be adjusted to give said flexible carrier any desired tension. A brake or friction device of any desired character may be used in 60 connection with the drum 14, for the purpose of holding said drum stationary except when the sprocket roller 19 is operated; and this brake or friction device may consist of a friction washer or washers 24 65 placed between one or both ends of said drum 14 and portions of the frame 13.

Fixed to the shaft 25 of the roller 19 is a ratchet wheel 26 engaged by a detent pawl 27; and pivotally mounted on said shaft 25 is an operating crank or handle 28 carrying a spring-pressed pawl 29 which may be actuated manually for imparting a partial rotary movement to the sprocket wheel roller 19, for the purpose of advancing the flexible carrier or belt, comprising the sprocket chains 16 and cross pieces 17, and thus discharge an article from said carrier or belt.

Connected with the operating crank or handle 28 is a link 30 carrying a pin 31 which, when the said crank or handle is moved forward, is so arranged as to come in contact with a shoulder 32 on a fixed plate or portion on the frame of the machine, and thus prevent a full movement of the said crank or handle so that the article carrier or belt will not be advanced a sufficient distance to discharge an article from the machine; but when a coin 33, which has been inserted in the coin chute 34, is in the position shown in Fig. 4 the said pin 31 will be lifted above the shoulder 32 and thus permit a full movement of the crank or handle 35 to discharge an article from the belt or carrier, the same passing down over a chute 36 into a receptacle 37 at the front of the machine.

When a coin is slipped into the coin chute it passes down the same by gravity until it is stopped by the pin 31 when the said pin is in the position denoted by dotted lines in Fig. 4, but when the said pin is lifted over the coin, so as to pass over the shoulder 32, the coin is released and may pass down the chute into a suitable drawer or receptacle 37. After the crank or handle 28 has been operated, as just described, and is released, it will be returned to its normal position by a coil spring 38.

105

110

The casing 12 is preferably provided in front with a door 39 having a lock 40, so that ready access is afforded to the interior of said casing when the machine is to be charged by loading the flexible carrier with the articles to be sold. When the machine is empty the carrier belt will be mostly wound on the drum 15, and as articles are placed on said carrier the drum 14 will be slowly turned by the crank 41 connected with the shaft 42 of the said drum 14 to wind up said carrier, now charged or loaded, on said drum 14.

The operation of the improved machine will be readily understood from the foregoing. When a purchaser wishes to obtain an article with which the machine is charged such person inserts a coin in the coin slot 43 in the casing. The coin passes down the coin chute 34 until it is stopped by contact with the pin 31 against which it rests temporarily. The handle 28 may now be operated by its knob 28^a and as said handle is moved forward the engagement of said pin 31 with the coin causes said pin to be lifted above the stop shoulder 32, so that a full movement of the said handle is permitted to discharge an article from the flexible carrier into the receptacle 36. When the said pin passes forward over said stop shoulder the coin is released and passes down its chute into the coin receptacle 37 or where else it may be desired to deposit it. The operating handle 28, when released, is returned to its normal or first position by the spring 28, and the machine will thus be set in readiness for the next operation.

Having thus described my invention I claim and desire to secure by Letters Patent:

1. In a vending machine, the combination with a pair of spaced drums, of a flexible carrier connected at its opposite ends to said drums and being of a length to permit coiling of the same respectively about said drums, cross pieces connecting said carrier, and means comprising outwardly projecting plates carried by said carrier adapted when said carrier is coiled on said drums to form

side walls of compartments in which the goods to be dispensed are housed. 50

2. In a vending machine, the combination with a pair of spaced drums, of a flexible carrier connected at its opposite ends to said drums and being of a length to permit coiling of the same respectively about said drums, cross pieces connecting said carrier, means comprising outwardly projecting plates carried by said carrier adapted when said carrier is coiled on said drums to form side walls of compartments in which the goods to be dispensed are housed, and an operating roller having positive engagement with said carrier for advancing the same step by step. 55

3. In a vending machine, the combination with a pair of spaced drums, of a flexible carrier connected at its opposite ends to said drums and being of a length to permit coiling of the same respectively about said drums, cross pieces connecting said carrier, means comprising outwardly projecting plates carried by said carrier adapted when said carrier is coiled on said drums to form side walls of compartments in which the goods to be dispensed are housed, an operating roller having positive engagement with said carrier, and means carried by said roller for causing a step by step advancement of said carrier. 75

4. In a vending machine, the combination with a pair of spaced drums, of a flexible carrier connected at its opposite ends to said drums and being of a length to permit coiling of the same respectively about said drums, cross pieces connecting said carrier, means comprising outwardly projecting plates carried by said carrier adapted when said carrier is coiled on said drums to form side walls of compartments in which the goods to be dispensed are housed, and intermittently operable means carried by said roller for causing a step by step advancement of said carrier. 85 90

In testimony whereof I affix my signature.

JOHN A. RAY.
